UNITED STATES PATENT OFFICE.

WILLIAM A. P. BICKNELL, OF RIVERDALE, NEW YORK COUNTY, NEW YORK.

AIR-COMPRESSOR.

SPECIFICATION forming part of Letters Patent No. 273,014, dated February 27, 1883.

Application filed September 19, 1882. (No model.)

To all whom it may concern:

Be it known that I, WILLIAM A. P. BICKNELL, of Riverdale, in the city, county, and State of New York, have invented certain new and useful Improvements in Air-Compressors, of which the following is a full, clear, and exact description.

The object of my invention is to provide certain new and useful improvements in air-compressors, whereby the valve leading to the discharge-chamber or compressed-air receiver will be open when the pressure of the compressed air in the cylinder is equal to the pressure of the air in the compressed-air chamber, but will not be open to any appreciable extent before that moment, and whereby it will close quickly at the end of the stroke, thus preventing any air from finding its way back as the piston recedes, and whereby said valve may be proportioned to give good results up to a piston speed of five hundred feet per minute.

The invention consists in a discharge-valve for air-compressors, which is formed of a valve mounted on the same spindle with two pistons adapted to move in small cylinders or chambers which have one end in communication with a cylinder and the other end in communication with a chamber, which, in turn, is in communication with a compressed-air receiver, whereby the valve will be open when the air in the compressor-cylinder has the same pressure as that in the compressed-air receiver, which valve also closes rapidly as soon as the piston reaches the end of the stroke and before it begins to recede.

Reference is to be had to the accompanying drawings, forming a part of this specification, in which similar letters of reference indicate corresponding parts in all the figures.

Figure 1 is a longitudinal sectional elevation of one end of the cylinder of an air-compressor provided with my improvements. Fig. 2 is a like longitudinal sectional elevation, showing a modification of the same.

The cylinder A contains the piston B, which is attached to a piston-rod, B', and is reciprocated in the cylinder, as in air-compressors of the usual construction. The cylinder is provided with inlet-ports C, which are closed by an inwardly-opening spring-valve, D, of any suitable construction. The compressed air ~~ss~~ out of the cylinder through the ports

E E into a chamber, S, which ports E E can be closed by a valve, F, mounted on a spindle, I, which is mounted in such a manner that it can slide in the direction of the length of the cylinder. A spring, V, surrounding the spindle I, presses the valve F toward the outer surface of the end of the cylinder.

The tube J conducts the compressed air from the chamber S to the receiver for compressed air. Adjoining the chamber S a chamber, K, is formed, which contains two pistons, L and M, which are made integral, and are mounted on the spindle I, the piston L being larger than the piston M. The said chamber K is of such size that the disks L and M fit closely therein; but both can have a slight movement in the direction of the length of the spindle I. By means of a channel, m', that part of the chamber K between the smaller piston M and the wall of the chamber is in communication with the chamber S, and by means of the tube G that part of the chamber K between the larger piston L and the wall of the chamber is in communication with the cylinder A. The distance from the cylinder end of the channel G to the nearest inner end surface of the cylinder must be greater than the thickness of the piston B, so that when the piston B rests against the end of the cylinder the piston will not close the channel G. The channel G is provided with a cock, H, for a purpose that will be specified hereinafter. By means of a short channel or aperture, n, the outer part of the chamber K is in communication with the outer air.

In the modification shown in Fig. 2, in place of the disk-valve F, a gridiron-valve, F', is used, and it is also attached to the spindle I', on which the pistons L' and M' are mounted.

The operation is as follows: The piston has been moving in the inverse direction of the arrow a', and has just compressed the air before it to the pressure of the air in the receiver for compressed air. The pressure upon the pistons L and M is thus the same, for the short cylinders in which they work are in communication with the cylinder A and with the chamber S by means of the channels G and m', the pressure in the chamber S being the same as the pressure in the compressed-air receiver. The piston L is of larger area than the piston M, and the pressure on the same has therefore overbalanced the pressure upon the piston M

and opened the valve F, which closed the ports E, thus permitting the compressed air to pass through the ports E, the chamber S, and the tube J to the compressed-air receiver. When 5 the piston reaches the position shown in dotted lines it has passed beyond the cylinder end of the channel G, thus permitting the compressed air to escape from behind the piston L. The pressure on the piston M can then push the said 10 piston in the direction of the arrow a', thereby pressing the valve F upon the ports E, which are thus closed. The spring V closes the valve F in starting the machine when there is no pressure in the compressed-air chamber.

15 The device shown in Fig. 2 operates the same as the device shown in Fig. 1, with the exception that the spindle I' moves at right angles to the longitudinal axis of the cylinder, whereas in the device shown in Fig. 1 it moves parallel with the same. When the compressor is running at lower speed than that for which it is designed, the valve F will be opened and closed sooner than is necessary; but this can be remedied by means of the cock H, by means of 20 which the transverse area of the channel G can be so adjusted that the valve F is opened and closed at the proper time.

25 By using my above-described improved discharge-valve a great amount of power is saved, for the valve F will always be open, if the pistons M and L are correctly proportioned, when the pressure in the cylinder A is equal to the pressure in the compressed-air receiver, whereas in the compressors provided with the usual 30 discharge-valve, when running at high speed, the pressure in the cylinder often exceeds the pressure in the compressed-air receiver considerably, because of the inertia of said valves when closed and the extra pressure in the cylinder required to overcome said inertia and open them quickly, thus causing a great loss of power.

35 The above-described valve requires no adjustment for different degrees of compression, but will always be self-acting and self-adjusting, and will close rapidly when the piston reaches the end of the stroke.

40 An additional opening from the channel G into the cylinder, near the head of the same, 45 may be provided to maintain communication

between said passage and the cylinder while the piston-head is passing the first opening at the completion of its strokes.

Having thus fully described my invention, I claim as new and desire to secure by Letters Patent—

1. The combination, with an air-compressor cylinder, of a discharge-valve mounted on a spindle on which are mounted two pistons of different sizes, which pistons move in short cylinders in communication with the air-compressor cylinder and with the compressed-air receiver, substantially as herein shown and described, and for the purpose set forth.

2. The combination, with an air-compressor cylinder, of a discharge-valve mounted on a spindle on which are mounted two pistons of different sizes, which pistons move in short cylinders in communication with the air-compressor cylinder and with the compressed-air receiver, and of devices for adjusting the transverse area of the channel connecting one of the said small cylinders with the compressed-air cylinder, substantially as herein shown and described, and for the purpose set forth.

3. In an air-compressor, the combination, with the compressor-cylinder A and piston B, of the discharge-valve F and pistons L M, of different diameters, the valve and pistons being on the same spindle, I, chambers S and K, connected by a channel, m', and tube G, connecting the opposite end of the chamber K with the compressor-cylinder, substantially as described, and for the purpose set forth.

4. In an air-compressor, the combination, with the compressor-cylinder A and piston B, of the discharge-valve F, spring V, and pistons L M, of different diameters, the valve and pistons being on the same spindle, I, chamber K, provided with a channel or opening, n, chamber S, communicating with the chamber K by a channel, m', and tube G, provided with a cock, H, and connecting the opposite end of the chamber K with the compressor-cylinder, substantially as described, and for the purpose set forth.

WM. A. P. BICKNELL.
